Application December 20, 1947, Serial No. 792,996

17 Claims. (Cl. 235—89)

1

The present invention relates to calculators of the slide rule type and more particularly to calculators for giving the answer, decimal point included, corresponding to a given set of data.

It is an object of the present invention to provide an improved calculator of the slide rule type in which the decimal point is located automatically as an incident to the setting of the slider in accordance with supplied data. It is a related object to provide a calculator which is particularly well adapted for performing calculations which include large multiplying factors such as those used in computing safety rates.

It is another object to provide a slide rule type calculator in which a single table of answer data is utilized in a number of different calculations, for example, those calculations required for determining accident frequency and severity rates.

It is a further object to provide a calculator which may be constructed to occupy a volume less than that of the small slide rule while enabling four-place accuracy or greater. It is an allied object to provide a calculator which requires no technical skill in its operation and which may be used by a layman without mathematical experience with perfect reliability. Since a computation requires but a single setting of the device the correctness of the answer may be verified merely by inspection and without the necessity for checking.

It is still another object to provide a calculator which is not only simple and straightforward of construction and attractive in appearance but also one which is easily and cheaply manufactured from readily available materials and using conventional printing arrangements.

Other objects and advantages of the invention will be apparent from the following detail description taken in connection with the accompanying drawings, in which:

Figure 1 is a general view of a calculator constructed in accordance with our invention and with the portion of the face removed to show the tabulation of data on the slider.

Fig. 2 is a fragmentary view of a portion of the calculator showing the position of the slider in an exemplary computation.

Fig. 3 is a fragmentary view similar to Fig. 2 but showing the relative position of the slider in another exemplary computation.

Fig. 4 is a cross sectional view of the calculator disclosed in Fig. 1 and showing the laminated construction.

While the invention is susceptible of various modifications and alternative constructions and

2

uses, we have shown in the drawings and will herein describe in detail one embodiment of the invention. It is to be understood, however, that we do not intend to limit the invention by such disclosure, but aim to cover all modifications and alternative constructions and uses falling within the spirit and scope of the invention as expressed in the appended claims.

In the periodic reporting of injuries and accidents for statistical purposes, it is necessary for the safety engineer to work out various "frequency rates" and "severity rates" which are determined by the application of standard formulas devised by the American Standards Association. Such formulas require the use of data compiled by the reporting company on the number of injuries or accidents and the total number of man-hours worked. In the case of computing severity rates it is necessary to take into account the number of days lost together with the arbitrary "time charges" which depend upon the extent or seriousness of the disability. In an analogous way the "frequency rates" of motor vehicle accidents may be determined in terms of the number of miles travelled by the vehicles in use.

While computing the frequency and severity rates is a relatively simple problem from a mathematical standpoint, nevertheless the standard formulas include factors of up to 1,000,000, the purpose of which is to avoid expressing the answer as a small decimal. Since the factors in addition to being large are not the same for the various types of calculations, it is found that many errors are made in the reported figures. Such errors have caused safety statistics to be misleading in some instances and in others have required careful investigation and rechecking to insure that the figures are accurate.

One of the most important reasons for the difficulties of computation and inaccuracy is the fact that the great majority of industrial plants are not sufficiently large to have a safety engineer trained in this type of statistical work. In the average case the rates are computed by a person having other duties occupying his attention or by a clerk who does not have the necessary background or skill to deal with the large numbers involved. Even the use of calculating machines is of little help since normal calculating machines are not well equipped to handle multiplication by a factor of 1,000,000. In general the use of conventional slide rules for this purpose is out of the question since they do not have the required accuracy and since the placement of the decimal

point is entirely dependent upon the knowledge and skill of the person making the calculation.

Referring now to Fig. 1 of the drawings, the improved calculator indicated at 10 will be seen to consist of two relatively slidable parts, a body 12 and a slider 14 contained therein. It will be observed that the body 12 is constructed of envelope shape being open at both its upper end 16 and its lower end 18. The ends of the body are cut away as at 16a, 18a to enable gripping of a moon-shaped portion of the slider 14. The body 12, as shown in Fig. 4, is preferably of laminated construction including a face 13 and a back 15. The face and back are separated by longitudinal spacers 17 at the edge portions of the body in order to provide a central space 19 for easy insertion of the slider.

Arranged on the slider 14 in horizontal rows 21 and vertical rows 20 are figures which together constitute a table 22 of answers to a problem to be performed. The answers are in the form of significant digits, in other words, the numerals or digits which will appear in the final answer but without location of the decimal point therein, somewhat similar to data obtained from an accurate slide rule of the conventional type. Location of such decimal point required for the final answer is accomplished by other portions of the calculator to be described.

In accordance with one aspect of the invention the face 13 of the calculator includes one or more windows, 24, 26, 28, 30 for viewing a selected portion of the table 22 on the slider. Turning attention now to the window 24 it will be seen that it has at its upper edge a set of reference figures or numerals 32 which are in general vertical alignment with the vertical rows of figures on the table 22. Thus, as the slider 14 is pulled downwardly the figures in the table will be seen to pass the reference figures 32 in aligned columns.

In order to determine the proper position of the slider 14 with respect to the body 12 for indicating the answer to a calculation, a second row or set of reference figures 34 is used. The row 34 is in the present instance positioned along the left-hand edge of the slider 14 with individual figures 36 in horizontal alignment with the rows 21 in the table 22. In the operation of the calculator the slider 14 is positioned so that a selected one of the reference figures 36 appears in a window 24a to the left of the window 24. Although a separate window is used for this purpose, it will be apparent that the invention is not so limited but would obviously include embodiments in which a single interconnecting window is used. As a matter of fact, the windows 24, 24a may, in the present arrangement, be considered merely right and left-hand portions of the same window.

The device thus far described may be utilized to obtain the significant digits in the answer to an arithmetic problem, even without location of the decimal point. Thus the first set of reference numerals 32 are preferably used as dividends while the second set of reference figures 34 constitute divisors. The figures in the table are calculated quotients, each of which occupies a position in the table 22 determined by the reference figures as coordinates. This may be made clear by a simple example. Taking the numeral 2 in the set of reference figures 32 and dividing it by, say, the figure 1,050,000 which is the third in the series of reference figures 34, a quotient or answer of 1905 is obtained which is printed at the coordinate point. This quotient as it appears in

the table does not, of course, have the decimal point properly located. It does, however, contain the significant digits of the answer to four places of accuracy. Each of the remaining figures in the table 22 is determined in the same manner preferably by the use of a calculating machine.

For the sake of simplicity and ready understanding, only a portion of the figures on the table 22 and only a portion of the reference figures 36 are shown. The remaining data on the slider may be readily filled in merely by following the pattern which has been set up, until all or a major portion of the slider area contains printed data of the type set forth. As an aid in completing the table 22 it will be noted that the reference figures 36 increase by increments of 25,000. The largest figure in the series, namely the one which would be found at the bottom of the row 34, could, if desired, be 9,975,000, which is one unit short of 10,000,000. The invention is not, however, limited to the particular figures set forth on the slider. The only limitation is that the table give the significant digits of the answer in coordinate location. Thus, the increment between successive figures in the row 34 and the range of such figures may be entirely determined by the specific requirements of the calculation to be performed. It has been our experience that the values given herein and disclosed in the drawings work out satisfactorily for safety rate calculations.

In using the device thus far described to obtain the significant digits of a quotient, it is merely necessary to draw the slider 14 downwardly until the desired reference figure in the row 34 appears at the edge of the window 24a, in other words, immediately under the word "hours." Taking the example mentioned above it will be assumed that the figure 1,050,000 is positioned at the upper edge of the window 24a whereupon the figure 1905 appears immediately under the reference number or dividend 2. That is to say, dividing 2 by 1,050,000 results in a quotient of 1905, expressed in significant digits. In a similar manner the quotient obtained by dividing 3 by the figure 1,050,000 will be found immediately under the figure 3 to be 2857. In a like manner all of the quotients corresponding to the dividends in the set 32 will be found in the window at the coordinate location.

In accordance with the present invention means are provided for not only enabling the significant digits of a quotient to be immediately read from the calculator, but the decimal point may also be located without any additional operation or effort on the part of the person performing the calculations. In accomplishing this the window 24 and its left-hand portion 24a are preferably covered by a transparent sheet material such as cellulose acetate or similar plastic film. Suitable indicia of the location of the decimal point are then applied to such transparent covering. The decimal indicia in the main portion of the window 24 preferably consist of horizontal rows of decimal points formed of dots of ink as at 38. For a given positioning of the slider, the decimal points 38 fall in successive figures in a horizontal row on the slider. In order to give meaning to such decimal location, it is desirable that the decimal point be simultaneously located in the corresponding reference figure 36 (here a divisor) appearing in the space 24a.

In the case of the reference figures 36, the decimal point is preferably located by means of the border or profile 39 on an opaque mask 40,

For example, the decimal indicum in the window 24a corresponding to the decimal indicia 38 consists of the short, vertical line 42. It will be noted that the line 42 is far to the right, permitting the figures in the row 34 to be viewed in full width. Thus the divisors appearing adjacent the line 42 will each be seven decimal places in length. Each "thousands" place is denoted by a comma 48.

In most practical calculations it will be desirable to use divisors which are considerably smaller than seven decimal places in length. For example, instead of using a divisor of 1,050,000, as in the sample calculation above, it may be desired to employ a divisor having one less decimal place, to wit, 105,000, while still enabling direct decimal reading of the quotient. This is accomplished in the present invention by providing means for shortening the divisor by one decimal place, here the short vertical line 46 which forms a portion of the contour of the mask 40, and by providing a correspondingly displaced set of decimal indicia 44. As disclosed in Fig. 1 these are located downwardly and one decimal place to the right of the decimal indicia 38. It will also be noted that the line 46 is downwardly and to the left of the line 42, previously referred to. The commas 48 are progressively shifted to the left to correspond with the change in decimal location. In a like manner a third horizontal row 50 of decimal indicia may be used together with four, five, and even additional levels of displaced indicia as required in the solution of the practical problem for which the calculator is to be used. Four decimal levels enable the use of divisors as small as 1,000, such range being satisfactory for all normal safety calculations.

The mask 40 has been used in preference to employing a diagonal series of decimal points at 39 since it hides the unused right-hand portion of the reference figure or divisor in the row 34. This enables the operator to locate a figure of reduced width and magnitude in the window 24a without any distraction whatsoever caused by the unused decimal places. It will be noted that both the decimal indicia as formed by the edge 39 and by the decimal points 38, 40, 48 appear in diagonal rows. This is one of the distinctive features of the present calculator and is indicative of the fact that as the number of places in the divisor decreases, the number of places in the quotient correspondingly increases. The decimal points 38, 44, 48 thus extend downwardly to the right while the decimal indicia 39 in the portion 24a of the window extend downwardly to the left. In each case the arrangement can be referred to as "stepped."

Having understood the physical construction of the calculator particularly as regards the window 24, and the decimal indicia associated therewith, it will be apparent to one skilled in the art that the calculator is adapted to perform simple problems of calculation which may be encountered in many fields of endeavor. The calculator has, however, been particularly satisfactory for solving the frequency rate formula which is to be found in the code of the American Standards Association and which is standard throughout the industry as a yardstick in determining how frequently injuries occur. This formula is as follows:

$$\frac{\text{Number of injuries} \times 1,000,000}{\text{Total man-hours worked}} = \text{Frequency rate}$$

If three injuries occurred during a period of

100,000 man-hours the frequency rate may be readily ascertained. The setting of the slider 14 corresponding to such calculation is shown at 68 in Fig. 2. Note that the slider 14 is positioned so that the number 100,000 appears under the word "hours" at the left-hand side of the window 24. Reading directly under "3" which corresponds to the number of injuries (and is so entitled), one finds the figure 30.00. This is the figure which is employed for statistical purposes and signifies that the frequency rate is 30 injuries for each 1,000,000 man-hours worked.

In accordance with another aspect of the invention the improved calculator may be utilized to produce quotients which are much smaller in decimal magnitude which is, for example, necessary where the calculation involves a factor of 1,000 rather than 1,000,000 employed in the previous calculation. This is the case when computing severity rates, another important safety statistic.

In the present instance the means utilized for producing smaller quotients is disclosed in association with the window 26 of Fig. 1. It will be noted that the opaque mask 52 at the left-hand portion of the window 26 and which corresponds to the mask 40 is substantially unchanged. Opaque masks 54 running from the top to the bottom of the window 26 are used to enable the decimal point to extend to the left and into the region occupied by the adjacent row of figures. At the upper portion of each of the masks 54 are decimal points 58 and additional ciphers 56 are used to fill in the space between such decimal point 58 and the portion 60 of the window which is to be occupied by the figure constituting the quotient. Decimal indicia 62 formed of printed dots on the transparent window material may be used in the same manner as disclosed in connection with the window 24.

The use of the windows 26, 28 in determining severity rates will be made clear by considering the formula which is used as a standard in such calculations. This formula appears as follows:

$$\frac{(\text{Number of days lost} + \text{time charges}) \times 1,000}{\text{Total man-hours worked}} = \text{Severity rate}$$

Suppose that in a period of 100,000 man-hours there had been accidents producing total lost time of 200 days and further that one of the accidents involved the loss of a thumb. Since the loss of a thumb results in a certain amount of permanent disability, such loss increases the rate of the industrial plant. A scale of time charges has been set up by the American Standards Association, a number of which are listed at 64 in Fig. 1. It will be noted at 66 in this scale that the loss of a thumb is counted as a penalty of 600 days, and thus it is necessary to add the two figures to produce an aggregate of 800 days lost.

To perform the calculation, window 28 is used, the slider 14 being positioned so that the reference figure 100,000 appears in the left-hand portion 28a of the window under "hours." Such positioning of the slider is shown at Fig. 3 of the drawings. The severity rate, indicated at 70 in Fig. 3, is thus 8.00.

It will be apparent that if 80 man-days had been lost in this period rather than 800 as in the foregoing example, the severity rate would then be read under the figure 80 in window 26 as .800. Similarly, if only 8 days were lost the rate is read as .0800. This serves to illustrate the wide range of rate which may be directly read on the present calculator.

As a further example of the manner in which the calculator may be employed to obtain a composite severity rate, let it be assumed that the number of days lost in 100,000 man-hours of work was 888. In order to obtain the severity rate it will be necessary to split such figure up into three parts, 800, 80 and 8 man-days. The respective severity rates of 8.000, .8000 and .08000 (as found above) are then merely added together to produce a resultant severity rate of 8.8800. The latter step is an extremely simple one and not appreciably subject to error.

The calculator is also ideally suited to obtain the frequency rate of motor vehicle accidents. In such case the row of reference figures above the window, in this case window 30, corresponds to the number of motor vehicle accidents while the reference figure at the left-hand portion of the window is read in terms of miles rather than hours. The frequency rate is obtained from the following standard formula:

$$\frac{\text{Number of accidents} \times 100,000}{\text{Miles travelled}} = \text{Frequency rate}$$

The rate may be read directly by setting the appropriate number of miles in the space provided and reading the rate under the appropriate number of accidents. The rate is in a coordinate position just as in the examples previously discussed.

It will be apparent to one skilled in the art that the invention disclosed herein is not limited to the specific form of safety calculator disclosed but obviously includes many other equivalent calculators which may be constructed utilizing the teachings disclosed herein. Calculators of this general type are of considerable utility in a wide variety of fields. In adapting the calculator for other specific calculations, it is merely necessary that rows of reference figures 32, 34 be set up covering the probable range of data to be supplied. It is further necessary that the coordinate point on the table 22 include the answer which should result from the use of such data, such answer being preferably calculated in the first instance by using mechanical or other type of calculator. Then the decimal indicia are added to the window or aperture through which the table 22 and the row 34 of reference figures are viewed. Such indicia are so located that the decimal point is properly placed in the answer automatically as an incident to properly locating the decimal point in the reference figure in the row 34, all as described in the examples given above.

While the invention has been described in connection with the preferred embodiment including a series of windows, it will be appreciated by one skilled in the art that the invention is not so limited but includes arrangements in which portions of the face 13 shown as opaque are made transparent. The present construction has the advantage that portions of the table 22 not of interest in a particular calculator are, for the most part, hidden from view thus reducing possible distraction and the chances of error to a minimum. Nor is the invention limited to calculators of generally rectangular shape but obviously includes constructions in which the relatively sliding surfaces are cylindrical or radially pivoted, completely analogously to the cylindrical and circular type of slide rules.

While both the construction and operation of the calculator will be apparent from the foregoing, it should be stated, for purposes of completeness, that the showing in Fig. 1 is simplified to the extent that certain figures in the table 22,

normally viewable through the windows 24, 26, 28, 30, have been omitted. In this way the positioning of the decimal points 38, 44, 50 on the transparent window material can be more readily seen.

We claim as our invention:

- 5 1. In a calculator the combination comprising a body member having a face portion, a slider insertable under said face portion, said slider having a table of answers thereon consisting of figures arranged in horizontal and vertical rows, a vertical row of reference figures alongside said table, a plurality of transparent windows on said face portion for viewing a selected horizontal portion of said table, a set of stepped decimal indicia on said face portion and cooperating with the reference figures in said vertical row so that upon sliding adjustment of said slider a selected one of said decimal indicia may be positioned relative to a selected one of said reference figures to properly locate the decimal point in the latter, a horizontal row of reference figures adjacent each of said windows respectively and arranged in respective alignment with the vertical rows of figures in said table, said windows having a second set of decimal indicia imprinted thereon in stepped relation and so related to said first decimal indicia that the answer corresponding to a selected pair of coordinate reference figures may be read off directly and with the decimal point automatically properly located therein.
- 10 2. In a calculator the combination comprising first and second relatively slidable members, said first member having a table of answers to a mathematical problem and having a vertical row of reference figures aligned with the respective answers corresponding thereto, said second member having a plurality of windows therein each having a horizontal row of reference figures positioned adjacent the edge thereof and aligned with the respective answers corresponding thereto, individual reference figures in the row associated with each of said windows differing only from corresponding reference figures in the remaining rows in the location of the decimal point, and means on said second member overlying at least a part of the data on said first member for locating the decimal point therein so that the correct answer including the decimal point may be read from said table at the coordinate corresponding to a selected pair of reference figures.
- 15 3. In a calculator the combination comprising first and second relatively slidable members, said first member having a table of answers to a mathematical problem and having a vertical row of reference figures aligned with the respective answers corresponding thereto, said second member having transparent portions and having vertically spaced horizontal rows of reference figures aligned with the respective answers corresponding thereto to adjacent said transparent portions, individual figures in each of the latter mentioned rows differing only from corresponding figures in the other rows in the location of the decimal point, and means on the transparent portions of said second member overlying at least the answers in said table for locating the decimal point so that the correct answer including the decimal point may be read from said table at the coordinate corresponding to a selected pair of reference figures.
- 20 4. In a calculator the combination comprising first and second relatively slidable members, said first member having a table of answers to a mathematical problem printed thereon and having a vertical row of reference figures aligned with the respective answers corresponding thereto, said

second member having a plurality of windows of transparent material therein each having a horizontal row of reference figures positioned adjacent the edge thereof and aligned with the respective answers corresponding thereto, individual reference figures in the row associated with each of said windows differing only from corresponding reference figures in the remaining rows in the location of the decimal point, means on said second member for selecting one of the reference figures in said vertical row upon relative slidable positioning of said members, and decimal points imprinted on the windows of said second member and overlying the table of answers on said first member for automatically locating one of said decimal points in the answer which lies at the coordinate corresponding to a selected pair of reference figures.

5. In a calculator the combination comprising a first member, a thin second member overlying said first member and relatively slidable with respect thereto, said first member having a table of answers to a mathematical problem expressed in the form of significant figures and having a vertical row of reference figures in alignment with respective answers corresponding thereto, said second member having a plurality of windows therein, each having a horizontal row of reference figures spaced along the edge thereof, individual reference figures in the row associated with each of said windows having the same significant digits and differing from corresponding reference figures in the remaining horizontal rows only in the location of the decimal point, means on said second member for selecting one of the reference figures in said vertical row upon relative positioning of said members, and means including masks having decimal indicia thereon associated with at least certain ones of said windows and superimposed on the data on said first member, said indicia being so positioned as to properly locate the decimal point in the answer corresponding to a selected pair of reference figures.

6. In a calculator the combination comprising first and second members in surface-to-surface sliding engagement, said second member presenting a horizontal edge portion cooperating with the surface of said first member and having a horizontal row of reference figures thereon, said first member having a table of figures thereon arranged both in horizontal rows parallel to said horizontal edge portion and in vertical rows in alignment with individual ones of the figures on said edge portion, said first member also having a vertical row of reference figures adjacent said table and in horizontal alignment therewith, said second member having a series of stepped masks extending from said edge portion and overlying the vertical rows in said table and having a stepped mask overlying said vertical row of reference figures, said latter named mask being stepped in a direction opposite to said series of masks said figures being so related that a coordinate figure in said table selected by relative positioning said members is the quotient of a problem in which corresponding reference figures in the horizontal and vertical rows constitute the dividend and divisor.

7. In a calculator the combination comprising a first member, a second member overlying said first member and in surface-to-surface sliding engagement therewith, said second member presenting an edge portion cooperating with the surface of said first member and having a horizontal row of reference figures spaced therealong, said

first member having a table of figures thereon arranged both in horizontal rows parallel to said edge and in vertical rows which are aligned with individual ones of said figures on said edge portion, said first member also having a vertical row of reference figures adjacent said table and in horizontal alignment therewith, a mask adjacent to said edge portion and overlying said table, said mask including a series of diagonally arranged decimal indicia for each of the vertical rows of figures on said first member, said figures being so related that a given coordinate figure in said table includes the significant figures of an answer to a problem in which the corresponding reference figures in the horizontal and vertical rows constitute the supplied data, said decimal indicia being so arranged that when said members are relatively positioned to properly place the decimal point in a selected reference figure in the vertical row, the decimal is also properly placed in the answer.

8. In a calculator the combination comprising a first member, a second member overlying said first member and in surface-to-surface sliding engagement therewith, said second member presenting an edge portion cooperating with the surface of said first member and having a horizontal row of reference figures spaced therealong, said first member having a table of figures thereon arranged both in horizontal rows parallel to said edge and in vertical rows which are aligned with individual ones of said figures on said edge portion, said first member also having a vertical row of reference figures adjacent said table and in horizontal alignment therewith, a mask adjacent to said edge portion and overlying said table, said mask including a series of stepped decimal indicia for each of the vertical rows of figures on said first member, said figures being so related that a given coordinate figure in said table includes the significant figures of the quotient of a problem in which the corresponding reference figures in the horizontal and vertical rows constitute the supplied dividend and divisor, said decimal points being so stepped that when said members are relatively positioned to properly place the decimal point in a selected reference figure in the vertical row, the decimal is also properly placed in the quotient.

9. In a calculator the combination comprising a first member, a second member overlying said first member and in surface-to-surface sliding engagement therewith, said second member presenting an edge portion to said first member and having a row of reference figures spaced therealong, said first member having a table of figures thereon parallel to said edge portion and in vertical alignment with individual ones of the reference figures on said edge portion, said first member also having a reference figure thereon adjacent said table, said second member having a mask joined to said edge portion and overlying said first member, said mask including rows of diagonally arranged decimal points, one row for each of said reference figures, all of said figures being so related that a given figure in said table includes the significant digits of the answer to a problem in which the corresponding reference figures constitute the supplied data, said decimal points are so arranged on said mask that when said members are relatively moved to properly place the decimal point in the reference figure on said first member, the decimal point is also properly placed in the answer.

10. In a calculator the combination comprising

a first member, a second member overlying said first member and in surface-to-surface sliding engagement therewith, said second member presenting an edge portion to said first member and having a row of dividends spaced therealong, said first member having a row of quotients thereon parallel to said edge portion and in alinement with individual ones of the dividends on said edge portion, said first member also having a divisor adjacent said table, a mask stationarily mounted with respect to said edge portion and overlying said table, said mask including rows of diagonally arranged decimal points thereon for the figures on said first member, said decimal points being so arranged that when said members are relatively moved to properly place the decimal point in the divisor, the decimal points are also properly placed in each of said quotients.

11. In a calculator the combination comprising first and second members in surface-to-surface sliding engagement, said second member including a transparent mask portion having a horizontal row of dividends spaced therealong, said first member having a table of quotients in vertical alinement with individual ones of the dividends on said edge portion, said first member also having a vertical row of divisors adjacent said table, said mask having rows of diagonally arranged decimal points indicated thereon, one row for the row of dividends and one row for each of the rows of quotients, said decimal points being so arranged that when said members are relatively moved to properly place the decimal points in a selected one of the dividends on said first member, the decimal point is also properly placed in each of the corresponding quotients.

12. In a calculator the combination comprising a first member having a divisor and a row of quotients alined therewith, a second member slidable on said first member and having a window of transparent material for observing said divisor and said quotients, a set of dividends arranged adjacent said window and alined with corresponding quotients on said first member, said window having diagonal rows of decimal indicia arranged to overlie said divisor and said quotients, said decimal indicia being so arranged that relative movement of said members to position a decimal point in a desired position in said divisor automatically causes decimal points to be properly positioned in all of the quotients alined therewith so that a quotient corresponding to a given dividend and including the decimal point may be read off directly.

13. In a calculator the combination comprising a first sheet member having a row of divisors and a table of quotients adjacent thereto, a second sheet member slidable on said first member and having means including a window of transparent material for observing said divisors and said table of quotients, a row of dividends arranged along the edge of said window and alined with corresponding quotients on said first member, a stepped opaque mask on said second member for overlying the row of divisors on said first member, said window having a diagonal row of decimal indicia adjacent each of said dividends and arranged to overlie said table of quotients, said decimal indicia being so arranged that relative movement of said members to position said mask in a predetermined position in a selected divisor automatically causes decimal points to be properly positioned in all of the quotients in alinement therewith so that a quotient corresponding to a

given dividend and complete with decimal point may be read off directly.

14. In a calculator the combination comprising a body member of envelope shape and open at at least one of its ends, a slider insertable within said body member, said slider having a table of figures printed in rows thereon, said body member having a plurality of windows of transparent material, any one of which may be selected for viewing said table upon withdrawing said slider an appropriate amount, each of said windows having a set of reference figures respectively alined with the rows of figures of said table, each of said windows also having a diagonal row of decimal indicia thereon for locating the decimal point in the vertical reference figures in said table when a selected portion of the latter is located under a selected window and additional diagonal rows of decimal indicia overlying the visible answer figures on said table so that the visible answer figures in said table corresponding to a given one of the reference figures may be read off directly with the decimal point properly placed.

15. In a calculator of the slide rule type the combination comprising a body member, a slider in said body member having a table of answers printed thereon, said body member having a window therein for viewing a selected portion of said table, indicia on said body and slider settable in accordance with supplied data for indicating the positioning of said slider required for exposing the portion of said table in which the answer corresponding to said supplied data is to be found, said window having means including a stepped border for cutting off the digits of lesser significance in the answers in said table and for locating the decimal points therein to enable direct reading of the answer.

16. In a calculator of the slide rule type the combination comprising a body member, a slider in said body member having a table of answers printed in vertical rows thereon, said body member having a window therein for viewing a selected portion of said table, indicia on said body and slider settable in accordance with supplied data for indicating the positioning of said slider required for exposing the portion of said table in which the answer corresponding to the supplied data is to be found, said window having stepped masks of opaque material cooperating with at least a portion of said vertical rows for cutting off the digits of lesser significance in the answers in said table, said masks being overprinted with ciphers for enabling the decimal point for one row to overlap the adjacent row.

17. In a calculator the combination comprising a body member having a face portion, a slider insertable under said face portion, said slider having a table of answers thereon consisting of figures arranged in horizontal and vertical rows, a vertical row of reference figures alongside said table, said face portion having a plurality of windows for viewing a selected horizontal portion of said table and a corresponding portion of said vertical row of reference figures, a first set of stepped decimal indicia so located on said face portion with reference to said windows as to cooperate with the vertical row of reference figures so that upon sliding adjustment of said slider a selected one of said decimal indicia may be positioned relative to a selected one of said reference figures to properly locate the decimal point in the latter, a horizontal row of reference figures adjacent said windows and arranged in respective

alinement with the vertical rows of figures in said table, said windows having a second set of stepped decimal indicia so related to said first set of decimal indicia that the answer corresponding to a selected pair of coordinate reference figures may be read off directly and with a decimal point automatically properly located therein.
